CIGARETTE MAKER

Milton T. Green, Bradford, Pa.

Application May 24, 1932. Serial No. 613,286

5 Claims. (Cl. 131—5)

This invention relates to cigarette makers and has for an object to provide a device of this character which will permit the packing of the tobacco to suit the individual user's fancy and will enable the cigarette paper to be simultaneously filled with tobacco and pushed off the maker readily for use thus promoting cleanliness and rapidity in the manufacture of cigarettes.

A further object is to produce a cigarette maker having a novel hopper for supplying a suitable quantity of tobacco to the packing tube so that the plunger will not become jammed but will pack the tobacco uniformly throughout the tube.

A further object is to provide a novel ejection sleeve and a spring controlled dog, the latter being carried by the plunger to engage the sleeve and expel the rolled paper cylinder from the packing tube at the same time the plunger forces the packed tobacco from the tube so that the rolled paper will be continually supported by the tube until completely filled with the packed tobacco and ejected as a completed cigarette.

A further object is to provide a light, strong, and inexpensive cigarette maker which will be formed of a few parts that will not easily get out of order.

With the above and other objects in view the invention consists in certain novel details of construction and combinations of parts hereinafter fully described and claimed it being understood that various modifications may be resorted to within the scope of the appended claims without departing from the spirit or sacrificing any of the advantages of the invention.

35 In the accompanying drawings forming part of this specification,

Figure 1 is a perspective view of the preferred form of cigarette maker,

Figure 2 is a longitudinal section through the 40 cigarette maker,

Figure 3 is a plan view of the cigarette maker,

Figure 4 is a cross-section taken on the line 4—4 of Figure 2,

Figure 5 is a cross section taken on the line 5—5 45 of Figure 2,

Figure 6 is a detail section showing the cigarette about to be filled and ejected,

Figure 7 is a detail view showing the cigarette being ejected and filled,

50 Figure 8 is an enlarged longitudinal section

through the plunger showing the dog and operating button therefor,

Figure 9 is a cross section taken on the line 9—9 of Figure 8, and,

Figure 10 is a longitudinal section of a modified 55 form of the invention.

Referring now to the drawings in which like characters of reference designate similar parts in the various views, 10 designates a hopper which preferably is formed of sheet metal and is provided with sloping bottom walls 11, best shown in Figure 5, which are spaced apart sufficiently at the bottom to provide a discharge slot 12. A false bottom 13 is disposed longitudinally of the hopper and terminates short of the slot 12, the forward 60 end of the false bottom being sloped downwardly and forwardly to provide a chute 14 which contacts with the front end wall of the hopper in discharging a small quantity of the tobacco through the slot 12 into a tube 15 which is formed integral 65 with the bottom of the hopper and extends forwardly beyond the hopper for approximately the length of the cigarette to be formed, and is extended rearwardly beyond the rear end wall of the hopper for a short distance. The tube is slit 70 longitudinally at the top, as shown at 16, from its free end to the front wall of the hopper to receive the hereinafter described ejector dog. The tube is also split at the rear projecting end and the sides thereof turned upwardly, as shown at 17 in 75 Figure 4. A flat strip 18 is crimped at the sides over said upturned portions of the tube and coacts therewith in forming a stop to limit movement of the plunger 19.

The plunger is preferably constructed of a 80 metal tube closed at the front end and provided at the rear end with a grip 20 which may be fixed to the plunger in any preferred manner. A helical spring 21 is seated on the plunger in front of the grip to cushion the shock of engagement thereof with the stop 18 when the plunger is moved to its forward limit of movement. The plunger is of sufficient length to extend all the way through the tube 15 when shoved to its extreme limit of forward movement in order to simultaneously eject the rolled cigarette paper and fill the same with packed tobacco from the tube, as will presently be described in detail.

The cigarette ejector comprises a sleeve 22 100

which is slidably mounted on the tube 15, and is normally positioned adjacent to the front wall of the hopper. The sleeve is operated by means of a dog 23 which is mounted on a pivot pin 24 in the plunger bore and is adapted to be thrust up through a slot 25 in the top of the plunger and, when the plunger is moved forwardly, the dog, in its dotted line position shown in Figure 8, will pass through a vertical slot 26 in the front wall of the hopper and engage the rear edge of the sleeve to slide the sleeve forwardly on the tube 15.

The dog is operated by means of a stiff wire 27 which is connected to the dog in advance of its pivot and extends rearwardly through the plunger. A push button 28 is slidably mounted on the rear end of the plunger and the wire is fixed to the button by means of a pin 29 or other suitable connector. Guide pins 30 are mounted in the push button and slidably extend into slots 31 into the end of the grip 20 to direct sliding movement of the push button. A helical spring 32 is mounted on the plunger between the push button and the grip and normally holds the push button at its outer limit of movement so that the dog 23 is held retracted into the bore of the plunger.

In operation the hopper may be filled with the particular grade of tobacco which pleases the taste of the individual smoker. The hopper may be held in the left hand and the forefinger held over the end of the tube 15, as shown in Figure 2. The plunger may now be reciprocated in the tube to push measured quantities or slugs of the tobacco forwardly into the tube in succession until the tube is filled with packed tobacco. By varying the pressure on the plunger the tobacco may be packed as tightly or as loosely as the maker desires.

The cigarette paper 33 is rolled upon the exterior of the tube 15, as shown best in Figures 6 and 7, in front of the ejector sleeve 22 and moistened to complete the cigarette wrapper. The plunger 19 is now moved forwardly by pressure on the button 28 which throws the dog 23 out from the tube during forward stroke of the plunger to engage the ejector sleeve 22 and slide the same forwardly to push the wrapper from the tube at the same time the plunger ejects the packed cylinder of tobacco from the tube 15 into the wrapper. Thus the cigarette wrapper and the cigarette filling will simultaneously be removed from the tube in a single operation and without damage to the wrapper or mutilation of the shape of the cigarette, since the wrapper is supported by the tube 15 constantly, while it is traveling off of the tube, as shown in Figure 7, and cannot bend, buckle, or in any way become distorted during the ejecting process.

In Figure 10 there is shown a modified form of the invention in which only the plunger and part of the hopper are modified. The plunger 34, in the modified form of the invention, preferably consists of a solid rod equipped at the rear end with a grip 35 and also with a spring 36 to cushion the shock of the plunger against the stop 18 during forward movement. A pin 37 is mounted in the plunger near the front end thereof and projects upwardly therefrom. This pin constitutes an ejector adapted to engage the ejector sleeve 22 when the plunger is shoved forwardly and push the wrapper from the tube 15 while the plunger is simultaneously pushing the packed tobacco from the tube into the wrapper as above described.

A tension ring 38 is fitted in a slot 39 formed in the hopper 10 and forms an abutment for contact with the spring 36 to limit forward movement of the plunger and also forms a guide ring for the plunger.

It is thought that from the above description the construction and operation of my invention will be fully understood without further explanation.

What is claimed is:

1. A cigarette maker comprising a hopper, a tube fixed to the hopper and extending along the bottom thereof and having both ends open and disposed beyond the ends of the hopper, there being a longitudinal slot in the tube, the hopper having walls sloping toward the tube, there being a slot at the bottom of said walls communicating with the slot in the tube, a false bottom in the hopper having a downwardly extending chute coaxing with an end wall of the hopper in delivering a small quantity of tobacco through said slot into the tube, a plunger in said tube, a sleeve slidably mounted on the tube, and an ejector carried by the plunger for engaging said sleeve.

2. A cigarette maker comprising a hopper having a slot in the bottom, a filling tube fixed to the hopper and extending along the bottom thereof, said tube being open at both ends and projecting beyond the ends of the hopper, the forward end of said tube being adapted to support a cigarette paper when rolled thereupon, there being a slot in the top of said tube extending throughout the length of the tube and communicating with the slot in the hopper, a sliding sleeve on said tube adapted to be disposed in rear of the cigarette paper when rolled upon said tube, a plunger in said tube for packing tobacco ahead of it into the slotted portion of the tube, and a projection on the plunger adapted to engage said sleeve and ride in said slot to eject the rolled cigarette paper simultaneously with movement of the plunger to eject the packed tobacco from the tube into the paper.

3. A cigarette maker comprising a hopper having a slot in the bottom, a filling tube fixed to the hopper and extending along the bottom thereof, said tube projecting at both ends beyond the hopper, one end of said tube having a slot communicating with the slot of the hopper and extending along the tube approximately the length of the cigarette to be formed, the other end of said tube projecting beyond the rear end of the hopper and forming a stop, a plunger in said tube having a grip adapted to engage with the stop and limit forward movement of the plunger, a spring on the plunger in advance of the grip adapted to cushion contact of the grip with the stop, a projection on the plunger adapted to ride in the slot of the opposite end of the filling tube, and an ejector sleeve slidably mounted on the tube and adapted to be engaged by said projection to slide the sleeve longitudinally of the tube.

4. In a cigarette maker, a hopper having a slot in the bottom, a filling tube fixed to the bottom of the hopper and extending longitudinally along the bottom of the hopper, said tube having a slot communicating with the slot in the hopper, a plunger in the tube, an ejector sleeve on the tube, a pivoted dog carried by the plunger and adapted to engage and move said ejector sleeve, and means on the plunger adapted to move said dog to operative position when the plunger is manually pushed forward.

5. A cigarette maker comprising a hopper having a slot in the bottom, a packing tube fixed to

the bottom of the hopper and extending longitudinally along the bottom of the hopper, said tube having a slot communicating with the slot in the hopper, a hollow plunger in said tube, a pivoted dog in the bore of the plunger and adapted to project through a slot in the plunger, a sliding ejector sleeve on the tube in the path of said dog, a knob slidably mounted on the plunger, a

spring holding said knob at one limit of movement and a wire connecting the dog with the knob for extending the dog to engage the sleeve when the knob is moved against the tension of said spring during manual movement of the plunger 80 forwardly in the tube.
